(57) CLAIM

I claim the ornamental design for a sports jersey, as shown and described.

DESCRIPTION

FIG. 1 is a front view of a sports jersey in accordance with a first embodiment of my new design;

FIG. 2 is a rear view thereof;

FIG. 3 is a first side view thereof;

FIG. 4 is a second side view thereof;

FIG. 5 is a top view thereof;

FIG. 6 is a bottom view thereof;

FIG. 7 is a front view of a sports jersey in accordance with a second embodiment of my new design;

FIG. 8 is a rear view thereof;

FIG. 9 is a first side view thereof;

FIG. 10 is a second side view thereof;

FIG. 11 is a top view thereof; and,

FIG. 12 is a bottom view thereof.

The dash-dot broken line portions are included to show unclaimed portions of the article only and form no part of the claimed design. The even dash broken lines represent stitching that forms no part of the claimed design.

1 Claim, 8 Drawing Sheets
